UNITED STATES PATENT OFFICE.

BAXTER D. WHITNEY, OF WINCHESTER, MASSACHUSETTS.

WOOD-PLANING MACHINE FOR CURVED WORK.

SPECIFICATION forming part of Letters Patent No. 664,519, dated December 25, 1900.

Application filed March 16, 1897. Serial No. 627,875. (No model.)

To all whom it may concern:

Be it known that I, BAXTER D. WHITNEY, a citizen of the United States, residing at Wincendon, in the county of Worcester and State 5 of Massachusetts, have invented a new and useful Improvement in Wood-Planing Machines for Curved Work, of which the following is a specification, reference being had to the accompanying drawings, forming a part 10 of the same, in which—

Figure 1 represents a side elevation of a wood-planing machine embodying my invention. Fig. 2 is a vertical sectional view on a plane parallel with the axes of the cutter-heads. Fig. 3 is a vertical sectional view on a plane at right angles with the axes of the cutter-heads. Fig. 4 represents a side elevation of the machine with the side frame A' and the driving-pulleys removed. Fig. 5 represents one end of the pressure-bar and one of the springs for applying pressure thereto; and Fig. 6 represents a curved chair-back, illustrating the character of work for which my improved planing-machine is adapted.

Similar letters refer to similar parts in the different figures.

My present invention relates to a wood-planing machine designed for planing the curved surfaces of chair-backs and similar 30 pieces of wood which are formed in the arc of a circle; and it consists in the construction and arrangement of parts, as hereinafter described, and set forth in the annexed claims.

Referring to the drawings, A and A' are 35 two upright side frames which support the operative parts of the machine. The side frames A A' are provided on their inner sides with horizontal flanges A² A², upon which the wedges A³ A³ rest. The wedges A³ A³ 40 support a vertically-adjustable framework consisting of the sides A⁴ A⁴, which are provided at their lower edges with inclined flanges A⁵ A⁵, resting upon sliding wedges A³ A³, and a curved top A⁶, which forms a supporting-table for the work after it passes the lower cutter-head. The sides A A' are 45 provided on their inner sides with horizontal flanges A⁷ parallel with the flanges A², and between the flanges A⁷ and the inclined flanges A⁵ are sliding wedges A⁸ A⁸. Pivoted at A⁹ in the sides A⁴ is a curved table A¹⁰, upon which the work is supported as it approaches

the cutter-heads. The wedges A³ A³ are connected by a cross-bar A¹¹, provided with a dependent lug A¹², in which is journaled a screw 55 A¹³, engaging a fixed nut held by the framework of the machine and carrying at its outer end a hand-wheel A¹⁵, by which the wedges A³ A³ are moved along upon the horizontal flanges A² A² for the purpose of raising or 60 lowering the work-supporting tables A⁶ and A¹⁰. Projecting upwardly from the cross-bar A¹¹ is a lug A¹⁶, in which is journaled a screw A¹⁷, engaging a nut A¹⁸ in a cross-bar A¹⁹, which connects the upper wedges A⁸ A⁸. The 65 screw A¹⁷ is provided with a hand-wheel A²⁰, by which the screw is rotated to move the upper wedges A⁸ A⁸ longitudinally between the horizontal flanges A⁷ A⁷ and the inclined flanges A⁵ A⁵ for the purpose of clamping the 70 inclined flanges A⁵ A⁵ between the upper and lower wedges and holding them firmly in position. In order to raise the work-supporting tables A⁶ and A¹⁰, the upper wedges A⁸ are moved toward the front of the machine sufficiently to release the inclined flanges A⁵. The lower wedges A³ are moved toward the front of the machine, thereby raising the tables A⁶ and A¹⁰. The upper wedges A⁸ are 75 then drawn back by the upper screw A¹⁷ to again clamp the inclined flanges A⁵ between the upper wedges A⁸ and the lower wedges A³. As the upper adjustable screw A¹⁷ is journaled in the lug A¹⁶, which is carried by the cross-bar A¹¹, connecting the lower wedges 80 A³, the rotation of the hand-wheel A¹⁵ alone will move both the upper and lower wedges simultaneously when the upper wedges have once been released. The sides A⁴ A⁴, by which the tables are supported, are provided 85 with mortises A²¹ to allow the cross-bar A¹⁹ to pass through and connect with the wedges A⁸ A⁸.

Supported by the sides A⁴ A⁴ is a bar B, which extends transversely through the machine 95 and is provided on its upper side with a rib B', entering a corresponding groove in a bar B², in which the shaft B³ of the lower cutter-head B⁴ is journaled. The bars B and B² are united by screws B⁵ B⁵, and by withdrawing 100 the screws B⁵ the upper bar B² and the cutter-head journaled therein can be drawn along the bar B and removed from the machine. Held in recesses in the bar B are wedges B⁶,

which bear against the under side of the upper bar B^2 and are adjusted by nuts B^7 in order to vary the position vertically of the bar B^2 , and thereby raise or lower the cutter-head B^4 relatively to the top of the work-supporting table A^6 .

The pivoted work-supporting table A^{10} is provided with an arm C , which extends rearward and carries an adjusting-screw C' , which 10 bears against a lug C^2 , projecting from the adjustable frame. A second screw C^3 passes through the arm C and is screwed into the lug C^2 , the screws C' and C^3 serving to vary the position of the arm C relatively to the lug C^2 15 and rock the work-supporting table A^{10} , so as to raise or depress the rear edge A^{22} of the table.

The table A^{10} has an extension A^{23} , providing an unobstructed curved surface upon which a curved chair-back, like that shown 20 at X , Fig. 6, can be placed and arranged with its concave side accurately fitting the convex surface of the table extension A^{23} , thereby 25 making the chair-back coincide with the table and preventing torsion of the back when the pressure is applied.

Journalized in boxes held in a fixed position and supported by the side frames A and A' is a shaft D , carrying the upper cutter-head D' , which is located in a vertical plane at the 30 rear of the lower cutter-head B^4 and above the rigid work-supporting table A^6 .

Arranged above the tables A^6 and A^{10} are feed-rolls D^2 and D^3 , carried upon shafts which are journalized in boxes capable of a slight vertical movement and acted upon by spiral springs D^5 , which are applied to press the boxes downwardly and have their tensions regulated by the adjusting-screws D^6 in the usual manner in wood-planing machines. 35 The feed-rolls D^3 are smooth; but the feed-rolls D^2 in front of the upper cutter-head are preferably fluted in order to engage the upper surface of the chair-back and draw it over the curved table A^{10} and project it forward over the table A^6 and beneath the upper cutter-head. The feed-roll D^{2a} , or the last feed-roll in the series of feed-rolls D^2 , is located over the front edge A^{24} of the rigid table A^6 , so that the yielding pressure applied by 40 the roll D^{2a} will serve to hold the lower planed surface of the chair-back in close contact with the upper surface of the table A^6 and cause the table A^6 to accurately gage the thickness of the finished chair-back, which will be equal 45 to the distance between the table A^6 and the path of the knife-edges of the upper cutter-head.

The adjustable table A^{10} is set with its rear edge A^{22} depressed slightly below the front edge A^{24} of the rigid table A^6 , the vertical difference between the planes of the two table edges being equal to the amount of stock removed by the lower cutter-head B^4 , so that the chair-back in passing beneath the feed-rolls D^2 and D^3 will be firmly supported by 60 both tables A^{10} and A^6 . The adjustment of the rocking table A^{10} relatively to the rigid

table determines the depth of the cut made by the lower cutter-head, and the vertical adjustment of the rigid table A^6 relatively to the upper cutter-head determines the thickness of the finished chair-back, and the adjustment of the lower cutter-head by means of the wedges B^6 and the nuts B^7 permits the lower cutter-head to be raised or lowered relatively to the upper surface of the rigid table A^6 , so as to make the circle described by the cutting edges of the knives of the lower cutter-head tangential to the circular plane of the rigid table A^6 . 75

The axes of the feed-rolls are arranged in the arc of a circle concentric with the circular arc of the table A^6 , and the shafts of the feed-rolls carry pinions D^7 , which are engaged by a rotating gear D^8 , carried upon a shaft D^9 , which is journalized in boxes supported by the side frames A and A' . The rotating gear D^8 is driven by a pinion D^{10} , carried by a shaft D^{11} , which extends transversely across the framework and is connected at the opposite side of the machine with the driving power. The rotating gear D^8 constitutes an annular rack rotating around the axis of the shaft D^9 , which is journalized concentrically with the curved surface of the rigid table A^6 , 90 causing all the feed-rolls to be simultaneously driven at a uniform speed.

Immediately in front of the upper cutter-head D' is a yielding presser-bar E , with its ends suspended from brackets E' , attached 100 to the fixed part of the machine, one of said brackets being shown in Fig. 5. The presser-bar E is supported by means of screw-threaded bolts E^2 , which pass through the brackets and are screwed into the end of the presser-bar. Each of the brackets E' is provided with a recess which contains a spiral spring E^3 , with its tension applied to force the presser-bar downwardly upon the work as it approaches the upper cutter-head. The presser-bar E is 105 maintained in an upright position and held from twisting or turning by means of tenons E^4 , projecting from each end and entering vertical grooves or ways in the framework, one of said tenons being shown in Fig. 5. 110 As the chair-backs pass through the machine they fall downward from the rigid table A^6 and are caught by a curved trough F , supported between the sides A and A' and sufficiently inclined to cause each chair-back to 115 slide from the rear to the front of the machine and be delivered at the lower end F' , thereby permitting the attendant who feeds the work to the machine to also remove the finished chair-backs from the same side of 120 the machine at which they are fed. The rear end of the inclined trough F is curved upwardly outside the path of the chair-back as it falls from the table A^6 , so that the falling chair-back will be caught by the curved rear 125 end of the trough; but sufficient space is left between the table A^6 and the rear end of the trough F to allow the planed chair-backs to be removed by an attendant, if required.

The sides A^4 A^4 of the inner and vertically-adjustable framework are provided on their outer sides with vertical ribs G. The rib G upon one side of the adjustable frame is shown in Fig. 4, the rib upon the opposite side, which is not shown, being the duplicate of that shown. The ribs G enter corresponding grooves in the stationary sides A and A' and serve as guides, so that the adjustment of the frame carrying the work-supporting table by means of the wedges A^3 A^3 will move the sides A^4 A^4 in a vertical plane.

The adjustment and operation of the machine are as follows: The lower cutter-head B⁴ is vertically adjusted by means of the wedges B⁶ to bring the cutting edges of its knives in proper position relatively to the surface of the rigid table A⁶. The table A⁶ is then adjusted relatively to the upper cutter-head D' to determine the thickness of the finished chair-back by means of the wedges A³ A³. When the proper adjustment of the table A⁶ has been accomplished, the inclined flanges A⁵ A⁵ are clamped against the adjusting-wedges A³ A³ by means of the clamping-wedges A⁸ A⁸, thereby maintaining the table A⁶ rigidly in its proper position relatively to the upper cutter-head D'. The rocking table A¹⁰, which is carried by the sides A⁴ A⁴ and has therefore been adjusted vertically with the table A⁶ by means of the wedges A³ A³, is then rocked upon its pivots A⁹ by means of the adjusting-screws C' and C⁸ in order to depress the rear edge A²² of the table A¹⁰ relatively to the front edge A²⁴ of the rigid table A⁶ and also to the path of the knife-edges of the lower cutter-head B⁴. This adjustment of the rocking table A¹⁰ determines the depth of the cut made by the lower cutter-head. The presser-bar E is then adjusted in proper position to cause the tension of the springs E³ to crowd the chair-back against the surface of the table A⁶, and the tensions of the springs E³ and of the feed-roll springs D⁵ are adjusted to provide the requisite pressure upon the chair-back. The chair-backs to be planed are placed upon the curved extension A²³ and are arranged thereon so that the curvature of the chair-back exactly fits the curvature of the extension A²³, which causes the axis of the curvature of the chair-back to coincide with the axis of the curved table A¹⁰, over which the chair-back is moved by the attendant until it is engaged by the feed-rolls D², which hold the chair-back in close contact with the table A¹⁰ and also move it forward over the lower cutter-head and upon the table A⁶, where it is engaged by the feed-roll D^{2a} and moved beneath the presser-bar E and the upper cutter-head and delivered over the table A⁶ by the rolls D³ into the upper end of the inclined trough F, by which the planed chair-back is returned to the front side of the machine.

What I claim as my invention, and desire to secure by Letters Patent, is—

1. The combination with a fixed framework

and a revolving cutter-head journaled therein, of a framework supported by said fixed framework and vertically adjustable therein, a curved work-table rigidly attached to said adjustable framework, a curved work-table pivoted on said adjustable framework and means for adjusting said pivoted curved table, whereby its plane is varied relatively to said rigid table, substantially as described.

2. The combination with the feed-tables A⁶ and A¹⁰ curved in the arcs of circles, of a lower cutter-head placed between the table A⁶ and the table A¹⁰, an upper cutter-head placed above the front edge of the table A⁶, a series of feed-rolls adapted to engage the work upon the side opposite said tables, and means for oscillating the table A¹⁰, whereby its front edge A²² is raised or lowered relatively to said lower cutter-head, substantially as described.

3. The combination with a fixed framework and a revolving cutter-head journaled therein, of a framework supported by said fixed framework and vertically adjustable therein, a curved work-table rigidly attached to said adjustable framework, a curved work-table pivoted on said adjustable framework, means for adjusting said pivoted table relatively to said rigid table and a series of pressure-rolls arranged above and concentrically with the curved work-tables, substantially as described.

4. The combination with a fixed framework and an upper cutter-head journaled therein, of an adjustable framework, a pair of sliding adjusting-wedges supported by said fixed framework and bearing against said adjustable frame, a pair of clamping-wedges between said fixed and said adjustable frameworks and acting in opposition to said adjusting-wedges to clamp said adjustable framework in position and connected means for moving said adjusting and said clamping wedges simultaneously, substantially as described.

5. The combination with a fixed framework, of a movable framework, a pair of adjusting-wedges by which said movable frame is raised, or lowered, means for sliding said adjusting-wedges, a cross-bar connecting said wedges, a lug projecting upwardly from said cross-bar, a pair of clamping-wedges acting in opposition to said adjusting-wedges, an adjusting-screw carried by said lug and engaging said cross-bar whereby said clamping-wedges are moved simultaneously with said adjusting-wedges and are capable of independent adjustment, substantially as described.

6. The combination with a curved work-table A⁶ and upper and lower cutter-heads D' and B⁴ of a pivoted curved work-table A¹⁰ provided with an arm C and adjusting-screws carried by said arm, whereby said table A¹⁰ is rocked relatively to the table A⁶ and held in position, substantially as described.

7. The combination with a curved work-table A⁶, of an inclined trough F located beneath said table having an upwardly-curved

rear end projecting beyond the curved plane of said table, substantially as described.

8. The combination of the curved work-supporting tables A⁶ and A¹⁰, a lower revolving cutter-head journaled between said tables and at one edge of table A⁶, means for vertically adjusting said tables, means for adjusting said table A¹⁰ relatively to the table A⁶, means for adjusting said lower cutter-head relatively to table A⁶, a feed-roll arranged over

the edge of table A⁶ and at the rear of the lower cutter-head and means for applying pressure to said feed-roll, substantially as described.

Dated this 10th day of March, 1897.

BAXTER D. WHITNEY.
